UNITED STATES PATENT OFFICE.

RANSOM D. PRATT, OF MARLBOROUGH, MASSACHUSETTS, ASSIGNOR OF TWO-THIRDS TO JULIAN P. WOOD AND HERBERT J. WILLARD, OF SAME PLACE.

ELECTRIC SWITCH.

SPECIFICATION forming part of Letters Patent No. 448,365, dated March 17, 1891.

Application filed July 7, 1890. Serial No. 358,024. (No model.)

To all whom it may concern:

Be it known that I, RANSOM D. PRATT, a citizen of the United States, residing at Marlborough, county of Middlesex, State of Massachusetts, have invented certain new and useful Improvements in Electric Switches, of which the following is a specification.

My invention relates to electric switches, and has for its object to produce a simple, cheap, and effective switch which is easily operated and not liable to get out of order; and to these ends my invention consists in a switch constructed, arranged, and operating substantially as hereinafter more particularly set forth.

In the accompanying drawings I have illustrated one embodiment of my invention, in which—

Figure 1 is a sectional view of an electric-light socket and switch. Fig. 2 is a transverse section thereof on the line $x-x$, Fig. 1; and Fig. 3 is a similar view showing the parts in different positions.

Heretofore electric switches have been made in many and various forms, and it has been proposed to make a switch operated by a push-button, in which the circuit was closed on pushing the button and opened on pulling the button. In other words, the different operations were necessary to produce the alternate opening and closing of the switch.

One of the features of my improved switch is that it is operated by a push-button, which is pressed in the usual manner of such buttons both to open and close the circuit, it standing in its normal position at all times when not pressed by the hand of the operator.

While the principles of my invention may be applied to many and various forms of switches, cut-outs, and the like, it is not necessary to show all the applications thereof; but in the accompanying drawings I have shown the switch applied to a socket of an incandescent electric lamp as being one of the uses to which it is adapted.

The socket, which may be in any well-known form, in the present instance consists of an inclosing case A, connected to a ring B, of non-conducting material, into which fits the screw-threaded tube C, which is adapted to receive the end of an electric lamp and to

make electrical connection with one of the electrodes thereof, the upper portion of the tube supporting an insulating plate or disk D, and connected to said plate is a binding-post C', to which one of the conductors P is connected. Mounted on this disk D is a plate E, preferably of spring material, bent up to form one of the contacts, and also connected to this plate is a tongue F, extending through an opening d in the center of the plate and forming a connection for the other electrode of the electric lamp when screwed in place in the socket; also, mounted on the plate D is an upright support G, having a plate H, secured thereto and extending practically parallel with the disk D. To this plate is secured a block I, of insulating material, on which is mounted a bent plate J, forming a binding-post for the other conductor, as N. This plate J is provided with an extension K, which is preferably bent in the form shown and arranged adjacent to the end of the plate E, which also is preferably bent to form a lip e.

Pivottally mounted on the insulating-block I is a switch-lever L, having an extension L', adapted to move between the lips K and e and to complete the electrical connection between them. These lips are arranged at an inclination, as shown in Fig. 1, so that the projection L' will rub against the lips and keep them bright and make good electric contact, and as the projection K is inclined from a central point and bears upon the extension L' of the switch it tends to hold it in position either open or closed, as the case may be, and when it is moved in either direction after passing the apex of the depression it tends to assist the switch in completing its movement. This switch L is operated by a push-button M, which moves in a socket O, secured to the standard G, and a spring Q normally keeps the push-button extended, as shown in Figs. 1 and 2, when not under pressure of the operator. Mounted on the push-button is a plate or rod R, which is of some spring material, and secured at one end to a lug or projection R', and thus moves with the push-button. The switch L is provided with a pointed projection L², having inclined sides and recesses l l' on either side. Normally this pointed or V-shaped projection L²

lies with its point at one side or the other of the path of the finger or rod R, as shown in Fig. 2.

The case A may have the usual cap-piece S 5 and a rubber or other gasket T, through which the conductors P and N pass.

Such being the construction, the operation of the switch will be readily understood.

In the position shown in Fig. 2 the switch 10 is closed, the extension L' being between the lips K of the plate J and e of the plate E, and when the push-button is pressed forward the rod R will impinge upon the inclined side of the point L² of the switch and pass down until 15 it reaches the notch l, when a further pressure will move the switch to break the connection, as shown in Figs. 1 and 3. As soon as the pressure is released from the push-button it will assume its normal extended position, the rod R being in the position shown 20 in dotted lines, Fig. 3. When it is desired to close the circuit, the push-button is again forced inward and the rod R will impinge upon the inclined side of the projection L² 25 and pass down to the notch l' and the switch will be rocked on its pivot, so that the extension L' will pass between the lips K and e and complete the electric connection. It will be seen that the bent lip K acts to prevent the 30 movement of the switch until the rod R reaches the notches l or l', as the case may be, and then assists in causing the switch to make a complete movement after it has once passed the apex of the projection. Thus the push- 35 button can be operated and pressed to a considerable extent without moving the switch, as the latter is not moved until the latter part of the movement of the push-button, and thus accidental pressures will not be liable 40 to move the switch, it requiring a complete movement of the button to operate the switch.

In order to make a double break-switch, so 45 as to break both the conductors leading to the lamp or other device and to close them simultaneously, the switch may be extended, as indicated in dotted lines, Fig. 3, and instead of the plate C', forming a binding-post, a contact-plate similar to plate E and a duplicate contact-plate J, serving as a binding- 50 post, may be supplied, as indicated in Fig. 3. Thus on each alternate movement of the switch both circuits will be broken or closed alternately.

55 While I have thus described and illustrated one and the preferred embodiment of my invention, it will be understood that the general principles thereof may be applied in many and various forms and arrangements without departing from the spirit of my invention, and I do not therefore limit myself to

the precise construction and arrangement of parts shown.

What I claim is—

1. An electric switch having contacts, a 65 pivoted bar to engage said contacts, provided with a V-shaped projection extending toward the push-button, a push-button for operating the bar, and a spring for retaining the push-button out of connection with the bar, the button being provided with a rod to engage the bar alternately at each side of the projection to open or close the circuit, substantially as described.

2. A switch having contacts, a pivoted bar 75 to engage said contacts, said bar having a V-shaped projection extending toward the push-button and provided with recesses at each side of the projection, and a spring-retained push-button provided with a spring-finger connected thereto to alternately engage the recesses at each side of the projection at each forward movement of the push-button, substantially as described.

3. An electric switch having contacts, a 85 pivoted bar to engage said contacts, a push-button for operating the bar, a spring for retaining the push-button in its normal condition away from the bar, and a rod on the push-button engaging the opposite side of the projection on the bar at each alternate forward movement, substantially as described.

4. A switch having contacts and a pivoted bar to engage said contacts, said bar having a V-shaped projection with recesses on each side 95 of the projection, in combination with a push-button having a spring-finger connected thereto to operate the switch-bar, substantially as described.

5. A switch having contacts, consisting of 100 plates having lips adjacent each other and a switch-bar arranged to pass between the lips, one of the lips being bent to hold the switch-bar in position, substantially as described.

6. An electric switch having the contact- 105 plates provided with lips arranged adjacent each other, a pivoted switch-bar to engage said lips, said bar having a V-shaped projection and recesses on each side of said projection, and a push-button carrying a finger to 110 engage the sides of said V-shaped projection and arranged to move the switch-bar only when the finger engages the recesses, substantially as described.

In testimony whereof I have signed my 115 name to this specification in the presence of two subscribing witnesses.

RANSOM D. PRATT.
